UNITED STATES PATENT OFFICE.

HARRY R. ROMBERGER, OF CHICAGO, ILLINOIS, ASSIGNOR TO CHICAGO CAR SEAL CO., OF CHICAGO, ILLINOIS, A CORPORATION OF ILLINOIS.

CAR-SEAL.

1,202,225.

Specification of Letters Patent.

Patented Oct. 24, 1916.

Application filed March 11, 1916. Serial No. 83,519.

To all whom it may concern:

Be it known that I, HARRY R. ROMBERGER, a citizen of the United States, residing at Chicago, in the county of Cook and State 5 of Illinois, have invented certain new and useful Improvements in Car-Seals, of which the following is a specification.

My invention relates to an improved car seal, and it consists in the constructions, 10 combinations and arrangements herein described and claimed.

An object of my invention is to provide an improved car seal provided with automatic double locking and guiding devices, which 15 positively prevent release or detachment of the seal without destruction of the latter.

A further object of my invention is to provide a strong and simple car seal which will be certain in action, and in which 20 neither end of the strap can be broken off and then reinserted in the seal case.

In the accompanying drawings: Figure 1 is a top face view showing the seal case and adjacent portion of the strap in one embodiment of my invention; Fig. 2 is a face view of the shackle end of the strap; Fig. 3 is an edge view of my improved seal in unsealed position, the seal case being shown in section along the line 3—3 of Fig. 1; Fig. 4 is 25 a similar view showing the strap in locked or sealed position; Fig. 5 is a section on the line 5—5 of Fig. 1; Fig. 6 is a top view of the resilient locking member, partly broken away for clearness; Fig. 7 is a view similar 30 to Fig. 3, showing a slight modification; and Fig. 8 is a top face view of the seal case shown in Fig. 7.

Referring to the drawings, 1 indicates a locking strap having a shackle end 3 of 40 reduced width provided with notches 4 to form a locking head 5. The other end of said strap is bent over to form an integral sealed case 6, the longitudinal edges 7 of said case being strongly crimped together, 45 and preferably spot-welded at 8 adjacent to the ends of the entrance slot 9 adapted to closely fit the reduced shackle end 3 of the strap. The strap 1 is provided with embossed portions, or projections, 19 and 20 50 adjacent to its respective ends, in order to prevent said strap being broken and its ends then surreptitiously forced through the entrance slot 9 of the case 6.

A resilient member 10 is firmly confined 55 within the seal case 6 and formed with a

forwardly-extending portion 11 provided with projections 12 for lockingly engaging the head 5 in the sealed position of the strap; said locking projections being provided with inclined front edges to facilitate 60 such engagement of the head therewith. The resilient member 10 is further formed with a pair of rearwardly-extending, spaced, auxiliary locking lugs 13 adapted to interlockingly engage the strap head 5 upon 65 the initial insertion thereof into the casing 6 and to guide said head into position for engagement with the locking projections 12. The casing 6 is formed with recesses 14 for receiving the spring lugs 13 and for permitting 70 passage of the strap head 5 past the ends of said lugs into interlocking engagement therewith. The lower wall of the casing is provided with an inwardly-projecting inclined shoulder 15 for insuring 75 positive locking engagement of the strap head 5 with the locking projections 12, and to constitute a stop for preventing excessive downward shifting of the forwardly-projecting portion 11 and auxiliary locking 80 lugs 13 by the strap head 5 bearing thereon during its insertion.

In the above description, it will be clear that in the operation of my invention the shackle end of the strap is inserted through 85 the entrance slot 9 of the casing 6 until the strap head 5 rides over the ends of the spring lugs 13. The strap is then slightly withdrawn until the head 5 is guided by said spring lugs 13 into position to be shifted 90 into locking engagement with the projections 12; the strap being then again pushed forward within the casing until said projections 12 are brought into locking engagement with 95 said head 5 and the strap thus positively held locked in position.

Figs. 7 and 8 illustrate a slight modification, in which the top wall of the seal casing is cut partly across at 16 and the portion 17 of said wall in front of said cut is bent 100 down to provide an entrance slot 18 thereabove for the shackle end of the strap. This provides a construction in which the seal case cannot be surreptitiously opened or the strap unlocked without destroying said case, 105 and constitutes a strong and safe construction without the necessity of spot-welding the side edges of the seal case as previously described.

I have illustrated and described preferred 110

and satisfactory constructions, but changes could be made within the spirit and scope of my invention.

I claim:—

- 5 1. In a car seal, a metal strip having one end formed with a locking head, the other end of said strip being bent over and secured along its edges to the body of the strip to form a casing, said bent over portion being transversely cut across a portion only of its width and having that portion between the strip end and such transverse cut depressed to provide an entrance slot above said depressed portion for the locking head, and means within said casing for lockingly engaging said head.
- 10 2. In a car seal, a metal strip having one end formed with a locking head, the other end of said strip being bent over and secured along its edges to the body of the strip to form a casing, said bent over portion being transversely cut across a portion only of its width and having that portion between the strip end and such transverse cut depressed to provide an entrance slot above said depressed portion for the locking head, and
- 15 3. In a car seal, a metal strip having one end formed with a locking head, the other end of said strip being bent over and secured along its edges to the body of the strip to form a casing, said bent over portion being transversely cut across a portion only of its width and having that portion between the strip end and such transverse cut depressed to provide an entrance slot above said depressed portion for the locking head, and

means within said casing for lockingly engaging said head.

3. In a car seal, a metal strip having one end reduced in width and formed with a locking head, the other end of said strip being bent over and secured along its edges to the body of the strip to form a casing, said bent over portion being transversely cut across a portion only of its width and having that portion between the strip end and such transverse cut depressed and spot welded to the body of the strip to provide an entrance slot above said depressed portion of proper width for snugly receiving said reduced end of the strip, and a member within said casing provided with means for lockingly engaging said head and with auxiliary means for initially interlockingly engaging said head and guiding the latter into locking engagement with said locking means.

In testimony whereof I affix my signature in the presence of two witnesses.

HARRY R. ROMBERGER.
